UNITED STATES PATENT OFFICE.

ORRELL ASHTON, OF LAWRENCE, MASSACHUSETTS, ASSIGNOR TO UNITED SHOE MACHINERY COMPANY, OF PATERSON, NEW JERSEY, A CORPORATION OF NEW JERSEY.

ASSEMBLING-MACHINE.

1,026,940.

Specification of Letters Patent.

Patented May 21, 1912.

Application filed December 26, 1907, Serial No. 407,993. Renewed February 23, 1912. Serial No. 679,497.

To all whom it may concern:

Be it known that I, ORRELL ASHTON, a citizen of the United States, residing at Lawrence, in the county of Essex and Commonwealth of Massachusetts, have invented 5 certain Improvements in Assembling-Machines, of which the following description, in connection with the accompanying drawings, is a specification, like reference characters on the drawings indicating like parts in the several figures.

This invention relates to machines for assembling parts of boots and shoes.

The present embodiment of the invention 15 is herein shown as an improvement upon the machine described in a prior application for Letters Patent filed August 13, 1906, Serial No. 330,705. It will be understood, however, that the invention is not restricted 20 in all of its features to embodiment in a machine of the particular type described in said application. The machine of said prior application has provision for inserting a fastening in the rear face of a last for the 25 purpose of securing the upper to the last.

Said fastening is inserted at a point removed from the sole and it is desirable at times to insert it at a point adjacent to the cone of the last. It is important that the 30 relative positions of the last and the mechanism for inserting said fastening be accurately determined in order that liability of the fastening failing to enter the last may be prevented. There is particular occasion 35 for an accurate position of the last with relation to said mechanism when the last is quite thin at the point at which the fastening is to be inserted, as is frequently the case.

An important feature of the present invention accordingly consists in the provision 40 in a machine having mechanism for inserting a fastening in the rear face of a last, of means for positioning relatively the last 45 and said mechanism to insure operation of said mechanism within the area of said face. The point in the width of the last at which the fastening is inserted is not dependent upon the position which is given the last by 50 the operator and the accuracy with which the fastening is inserted is rendered substantially independent of the skill of the operator. Moreover, in the use of a ma-

chine embodying the present invention the fastening may be given a predetermined 55 position with regard to the width of the last. The arrangement is preferably such that the fastening is inserted at a point at one side of a median line of said face. This feature is of particular advantage where the 60 back seam of the upper to be assembled is centrally located, since any danger of said seam being cut by the fastening as it is inserted is thereby avoided.

The machine to which the present invention is shown applied includes devices 65 for wiping the upper over the edge of the last and for pressing the upper into close engagement with the last adjacent to the sole, and means for securing the wiped-over 70 upper to an innersole mounted upon the last. In order that these parts may perform their respective functions with precision, it is desirable that the last be accurately positioned with relation thereto, since 75 an irregular action thereof upon the work may detract materially from the quality of the work performed.

Another feature of the present invention accordingly consists in means for locating 80 the last in a predetermined position with relation to the wiping mechanism. This positioning is preferably effected before the work is engaged by any of said parts.

The machine herein shown is equipped 85 with fastening-inserting mechanism occupying a stationary position as in the machine of said application, and the last, carrying parts to be secured together, is brought into operative relation to said mechanism by the 90 operator. In its movement into working position, the heel of the last is engaged at opposite sides by adjusting members which have contact with the work adjacent to the sole of the last. These members are held 95 yieldingly together and are separated by the last as it is moved between them so that they exert a forward wiping action upon the upper along the sides of the shoe at the heel. The members are arranged for equal movement in opposite directions, so that the lateral position of the rear face of the last adjacent to the sole is thus predetermined 100 regardless of the width of the last. To position that part of said face which is adjacent to the cone of the last, I have shown 105

a gage provided with converging surfaces formed to receive and position between them the thinner part of the rear end of a last adjacent to the cone. This gage is yieldingly sustained for movement with the last toward the fastening inserting mechanism as the last is brought into working position, so that the last may be advanced to a predetermined position regardless of the contour 10 of its rear face.

Other features of the invention, including details of construction and combinations of parts, will be hereinafter described and defined in the appended claims.

15 In the drawings, which illustrate a machine constituting one embodiment of the invention,—Figure 1 is a view in side elevation of said machine with parts broken away; Fig. 2 is a view in front elevation of 20 the upper portion of the machine, showing certain parts in section; Fig. 3 is a view in horizontal section showing the construction in detail of means for alining a shoe with fastening-inserting mechanism; Fig. 4 is a 25 view similar to Fig. 3 showing a shoe in operative position in the machine; Fig. 5 is a view in perspective of parts shown in Fig. 3, showing in detail certain parts of the 30 means for alining the shoe with fastening- inserting mechanism; Fig. 6 is a perspective view of certain parts of clutch mechanism with which the machine is equipped.

Referring to the drawings, the reference 35 numeral 3 indicates the driving shaft of the machine from which the power-actuated working parts hereinafter referred to are driven. Extending from front to rear of the machine is a stem 6, the forward end of which constitutes a rest 8 against which the 40 rear face of the work is brought. The stem 6 is inclined upwardly and forwardly and contains a driver 7 actuated in the manner described in said prior application. The stem 6 of the rest 8 is provided with a depending slotted extension resting in a vertical guideway in the frame. Within this slotted extension is arranged a clamping bolt 9 which retains the stem in position. It will be seen that this arrangement permits 45 vertical adjustment of the stem 6 and the parts mounted thereon which will be herein- after more particularly described. To support the shoe to be acted upon, the following improved mechanism is provided. A tubu- 50 lar post 10 is pivotally secured at 12 to the base of the machine for swinging movement longitudinally of the machine and receives a last supporting spindle 14, said spindle being arranged for longitudinal movement in 55 the post but restrained from turning move- ment therein by a pin and slot connection, as shown in Fig. 1. The spindle 14 is pro- 60 vided at its upper end with a heel pin 16 arranged upon a lateral extension 18 formed 65 upon the spindle. An adjustable knurled

sleeve 20 is threaded upon the spindle 14 at a point intermediate its ends. The lower face of the sleeve 20 is engaged by a lever 22 pivoted at the rear of the machine and pro- 70 vided with a slot at its forward end through which passes the spindle 14. The lever 22 has an orifice through which passes a rod 24 which is raised and lowered automatically by a cam upon the shaft 3. A spring 26 is interposed between the lever 22 and a nut 75 on the lower end of the rod 24, and a collar 28 is secured upon the rod 24 in position to bear upon the upper face of the lever 22. An adjustable stop 29 is provided to limit 80 upward movement of the lever 22.

Two work-adjusting levers 30 are mounted upon a ledge formed upon the machine frame and are provided at their forward ends with work-engaging members 32, said 85 members being adjustable longitudinally of the levers and being rounded off or beveled upon their edges. The levers 30 are pivoted upon studs 34 and are provided with inter- meshing segmental gears 36 which insure 90 their equal movement in opposite directions. Coiled springs 38 encircling the studs 34 press the levers 30 yieldingly together. The normal position of the levers 30 may be varied by adjustment of a screw 40 which is mounted upon the rear end of one of the 95 levers 30 and serves as a stop to limit ap- 100 proaching movement of the work-engaging members 32.

Projecting laterally from the rest 8 is a wing 42 upon which is sustained a depend- 105 ing stud 44. Mounted upon said stud 44 is a block 46 arranged for a limited turning movement about said stud. A work-adjust- 110 ing member or gage 48 is carried by the block 46 and is pivoted at 50 upon said block for movement about an axis at right angles to the stud 44. A spring-pressed plunger 52 received in a recess in the mem- 115 ber 48 and bearing upon a lug extending from the block 46 holds the member 48 yieldingly upwardly against the lower face of the stem 6. A coiled spring 54 encircling the stud 44 is arranged to hold the block 46 yieldingly outwardly against a stop 56.

The gage 48 is provided with a V-shaped 120 notch to receive the rear end of a shoe, the sides of the notch constituting converging surfaces adapted to deflect into a pre- determined position the portion of the shoe engaged thereby. The apex of the notch in 125 the gage 48 is arranged slightly at one side of the driver 7 in order that the fastening inserted by said driver may lie at one side of a median line of the rear face of the shoe, as is clearly shown in Fig. 4.

A carrier 62 for devices to be described is journaled at 64 upon the machine frame, as in the machine of the prior application referred to. The carrier 62 at its upper 130 end is provided with a rearward extension

carrying a cam roll 63 which is engaged by a cam 65 upon the shaft 3. A presser 66 is rigidly secured upon the lower end of the carrier 62 for engaging the rear of the last 5 adjacent to the sole. A wiper 68 having its forward end curved upwardly is rigidly secured to the carrier above the presser 66. As shown in Fig. 1 the wiper 68 projects forwardly to such an extent that it is engaged 10 by the shoe during a portion of the movement of the latter into engagement with the rest 8. Upon the carrier 62 is secured a driver casing in which a driver 67 is arranged for movement. The driver 67 is actuated by a lever 69 which is turned to raise the driver 67 by a cam 71 upon the shaft 3 and is moved in the reverse direction by a spring 73 as is more particularly pointed out in the prior application referred to. It will 15 be understood that suitable mechanism is provided to place automatically a tack in the path of the driver 67 and that an opening is provided in the wiper 68, as shown upon the drawings, through which a tack 20 is driven by the driver 67 through upper and counter into the innersole.

The clutch mechanism herein shown comprises a key 70 arranged to slide longitudinally of the shaft 3 in a groove formed 30 therein. The key 70 is provided intermediate its ends with a slot in which is received a collar 72. A pulley 74 is mounted upon the collar 72 to rotate freely thereon, but restrained from movement longitudinally thereof. A member 76 is mounted upon the shaft 3 in fixed relation thereto and is provided with a friction surface engaged by a corresponding surface upon the interior of the pulley 74. The pulley 74 35 moves longitudinally with the key 70 and the key 70 is pressed toward the member 76 by a spring 78 encircling the shaft 3. The clutch mechanism as thus far described is substantially the same as illustrated in the 40 prior application above referred to. A lever 45 80 is pivotally mounted upon a bearing encircling the shaft 3, said lever being provided at its lower end with a guideway for a slide 82. The path of the slide 82 is in line with the inner end of the key 70 and said slide is provided at its upper end with an inclined 50 face 84 arranged to be engaged by the end of the key 70 in the rotation of the shaft 3, the key being forced thus longitudinally of the shaft against the resistance of the spring 78 to release the clutch. The slide 82 is provided upon its rear portion with a stop surface 86 which is engaged by the key 70 at the end of a revolution of the shaft 3, and 55 thus serves to positively arrest said shaft. The lever 80 is arranged for a limited oscillatory movement upon its support, its movement being limited by a stationary stud 88 secured to the machine frame. A 60

rearward movement of the upper end of the lever 80. To prevent rebound of the shaft 3 at the end of a revolution, a pawl 92 is arranged in the path of the key 70 and is held yieldingly against a stop 94 by a spring-pressed plunger 96. It will be seen that while the pawl 92 does not interfere with movement of the shaft 3 in a left-handed direction, viewing Fig. 6, it prevents movement of said shaft in the reverse direction after the key 70 strikes the surface 86 upon the slide 82 at the end of a revolution. 70

The clutch mechanism herein shown and described is not claimed in this application but is covered by a separate application filed 75 Nov. 30, 1908, Ser. No. 465,076. 80

In the use of the machine shown, the parts of a boot or shoe having been loosely brought together upon a last in the manner indicated for example in said prior application, the last is placed upon the heel pin 16 and moved rearwardly into working position. In this movement the heel end of the last first engages and moves apart the members 32 which have contact with the sides 90 of the last adjacent to the sole. These members wipe the upper forwardly as the work is advanced between them and bring the upper and counter into close relation to the rear face of the last. They also press the 95 ends of the counter inwardly against the sides of the last and hold said ends from displacement during the operation of the machine. Said members also deflect the sole of the heel end of the last into a predetermined position since they are interconnected for equal movement in opposite directions. In the further movement of the last into working position the gage 48 is engaged by the middle portion of the last or by that 100 part adjacent to the cone, according to the adjustment which may be given the stem 6, and deflects this portion into a central position with relation to the notch formed in the gage. It will be understood that the 105 last is so sustained as to conform to the positioning action of the members 32 and the gage 48. This effect is secured by the loose fit of the last upon the pin 16 and also by arranging the spindle 14 so that a slight 110 lateral play is permitted as well as a slight turning movement of said spindle in the post 10. By the conjoint action of the members 32 and the gage 48 the rear face of the last is controlled in position. As shown 115 in Fig. 4, said face is guided into a position in which a median line thereof is at one side of the driver operating through the rest 8. Preferably the last is offset toward the side upon which the driver passage is 120 cut away. This form of driver passage is provided to facilitate the removal of obstructions should such lodge therein, and since it causes the tack to be unsupported upon one side, it is claimed it may have a slight 125

tendency to cause the tack to incline toward the open side of the passage. In the arrangement of the parts shown, it will be seen that the last is offset in the direction in which there is liability of the tack inclining, so that danger of the tack glancing from the end of the last should it assume a slightly inclined position is prevented.

In the movement of the last into working position after the members 32 have been engaged by the sides of the last, the margin of the upper extending above the sole at the rear of the last is engaged by the wiper 68 and pressed down upon the sole. The wiper 68 is of upwardly curved contour so that as the last moves into working position the pressure of the wiper upon the work is increased. It will be understood that the wiper 68 not only turns the upper down upon the sole at the rear but also presses the counter downwardly into proper position wherein its flange lies in close relation to the sole, or if a straight counter is used the edge thereof is turned down upon the sole by said wiper.

The last having been brought into working position, the operation of the machine is effected by depression of the clutch-controlling treadle. In the first part of the rotation of the main shaft 3, the rod 24 is elevated and produces an increased upward pressure upon the last, against the wiper 68. It will be observed that the pressure with which the wiper bears upon the work is controlled by the tension of the spring 26. In the further movement of the shaft 3, the carrier 62 is swung longitudinally of the shoe, the wiper 68 riding over the rear edge of the shoe and subjecting said edge to an increased pressure in its movement. Before the carrier 62 reaches the end of its forward movement a tack is driven into the rear face of the last by the driver working through the rest 8, and at approximately the end of said movement a tack is driven through the upper and counter into the innersole, as described in said prior application. The presser 66 co-operates with the wiper 68 to form a well defined edge at the rear of the shoe and also presses the counter and upper into close relation to the rear edge of the innersole. The pressure exerted by the wiper 68 upon the work may be increased or diminished by adjustment of the sleeve 20 upon the spindle 14, this adjustment being also used to accommodate lasts of different heights. It will be seen that as the wiper 68 moves over the work the last is slightly depressed. The downward yielding movement of the gage 48 about the pivot 50 is of advantage in this connection in that the gage is thus free to move downwardly with the last, and liability of the upper or counter being shifted upwardly upon the last by frictional engagement with said gage is obviated.

The position of the heel pin shown in full lines in Fig. 1 is adapted for full sized lasts. It will be observed that with this arrangement the extension 18 upon the spindle 14 provides an extended bearing for the cone of the last and thus supports the last firmly against the pressure of the wiper 68. Where very small lasts are employed it may be found desirable to turn the spindle 14 180° to bring the heel pin into the position shown in dotted lines in Fig. 1. This prevents the extension 18 from interfering with the movement of the last into engagement with the rest 8.

It will be seen that the members 32 and the gage 48 are arranged to accommodate lasts of different widths as well as lasts varying in height. As will be apparent from the drawings, the members 32, as the shoe is advanced between them, automatically adjust themselves to the width of the shoe. Also the notch formed in the gage 48 is of sufficient size to receive lasts the rear ends of which are quite blunt as well as those having rear ends of smaller widths. The gage 48 is carried by the rest 8 so that vertical adjustment of the latter to accommodate a change in height of the last effects simultaneous adjustment of the gage into proper vertical position to position that part of the last adjacent to the cone. It will also be observed that since the gage 48 is sustained for yielding movement in the direction of movement of the shoe into working position, said gage does not interfere with bringing the rear face of the last into engagement with the rest 8 whatever may be the width of the last or the curvature of its rear face viewed laterally.

The term "shoe" employed in the appended claims is intended to include the parts to be assembled arranged upon a last. For example, this term may include a last, an innersole secured to the sole of the last or arranged loosely upon the last, as the case may be, and a lined upper arranged loosely about the last and having positioned within the lining a suitable counter.

The present invention is not limited to the particular embodiment herein shown and described. The invention is of a generic character and may be embodied in a machine of quite different construction from that herein described.

The last supporting mechanism herein shown and described is not claimed in this application but is covered by a divisional application filed February 5, 1909, Serial No. 476,240.

Having described my invention, what I claim as new and desire to secure by Letters Patent of the United States is:—

1. A machine of the class described, having in combination, mechanism for inserting a fastening in the rear face of a shoe, and

means for relatively shifting said mechanism and the shoe laterally of the shoe into operative relation preliminary to the insertion of a fastening.

5 2. A machine of the class described, having in combination, mechanism for inserting a fastening in the rear face of a shoe, and means for determining the position in the width of said face at which the fastening is inserted.

10 3. A machine of the class described having, in combination, mechanism for inserting a fastening and means for determining the position of a shoe relative to said mechanism to insure that it shall receive a fastening in its rear face from said mechanism.

15 4. A machine of the class described having, in combination, mechanism for inserting a fastening, and means for determining the position of a shoe relative to said mechanism to insure that it shall receive a fastening in its rear face from said mechanism, said means being constructed to accommodate shoes of different sizes.

20 5. A machine of the class described, having in combination, mechanism for inserting a fastening, means for locating a shoe relatively to said mechanism in position to receive a fastening in its rear face from said mechanism and for simultaneously wiping the upper forwardly along the sides of a shoe at the heel.

25 6. A machine of the class described, having in combination, mechanism for inserting a fastening and a last supporter arranged for relative movement, and means for shifting relatively said mechanism and a last carried by said supporter to bring the rear face of the last into position to receive a fastening from said mechanism.

30 7. A machine of the class described, having in combination, a rest arranged to be engaged by the rear face of a shoe, mechanism for inserting a fastening in said face while in engagement with the rest, and means for adjusting the shoe into a predetermined relation to said mechanism in its movement into engagement with the rest.

35 8. A machine of the class described, having in combination, a rest arranged to be engaged by the rear face of a shoe, mechanism for inserting a fastening in said face while in engagement with the rest, a last supporter constructed to sustain a shoe pivotally in its movement into engagement with the rest, and means for swinging the shoe into operative position upon said supporter during said movement.

40 9. A machine for assembling parts of boots or shoes mounted upon a last, having in combination, means for wiping the upper over the edge of the last, means for automatically securing the wiped over upper to an innersole mounted upon the last and means for maintaining a predetermined

portion of the sole edge of the last in operative relation to said wiping means and said securing means constructed to restrain movement of the last in a direction lateral of the path of action of said wiping means.

45 10. A machine for assembling parts of boots and shoes mounted upon a last, having in combination, means for wiping the upper over the edge of the last, means for automatically securing the wiped over upper to an innersole mounted upon the last, and means arranged for engagement with opposite sides of the upper for guiding the last into a position wherein a predetermined point in the width of the last will be acted upon by the wiping means and the securing means.

50 11. A machine for assembling parts of boots and shoes mounted upon a last, having in combination, means for wiping an upper over the rear edge of the last, means for pressing the upper against the rear face of the last constructed for engagement with the upper at the sole edge, means for securing the upper to an innersole carried by the last, and means arranged for engagement with opposite sides of the upper for guiding the last into a position wherein a predetermined point in the width of the last will be acted upon by the wiping means, the pressing means and the securing means.

55 12. A machine of the class described, having, in combination, a last supporter arranged for movement to and from working position, means for wiping the upper over the rear edge of the last in the movement of the last into working position, means for bringing a predetermined portion in the width of the last into operative relation to said wiping means during said movement of the last, and means for securing the upper to an innersole mounted upon the last.

60 13. A machine of the class described, having in combination, means for automatically wiping an upper over the rear edge of the last, means for automatically securing the wiped-over upper to an innersole mounted upon the last, and means for restraining movement of the rear end of the last in a direction lateral of the path of action of said wiping means.

65 14. A machine of the class described, having in combination, mechanism for inserting a fastening in the rear face of a shoe and means for positioning in the path of the fastening a portion of said face at one side of a median line.

70 15. A machine of the class described, having in combination, a last supporter arranged for movement to and from working position, a wiper arranged in the path of the last for wiping the upper over the rear edge of the last, devices arranged in the path of the last for wiping the upper forwardly along the sides of the last, the rear, means

for securing the upper to an innersole mounted upon the last, and means for securing the upper to the rear face of the last.

16. A machine of the class described, having in combination, a last supporter arranged for movement to and from working position, means for wiping the upper over the rear edge of the last in the movement of the last into working position, means for guiding the last into a position wherein a predetermined point in its sole edge lies in operative relation to the wiping means and means for thereafter securing the upper to an innersole mounted upon the last.

17. A machine of the class described, having in combination, a last supporter arranged for movement to and from working position, a wiper arranged to ride over the edge of the last in the movement of the last into said position, means for automatically increasing the pressure of engagement of the wiper with the last, means for thereafter moving the wiper longitudinally of the last to subject the work to a further wiping action and means for securing the upper at approximately the end of said forward movement to an innersole carried by the last.

18. A machine of the class described, having in combination, a last supporter arranged for movement to and from working position, a wiper arranged in the path of the last for wiping the upper over the rear edge of the last, means for moving the wiper longitudinally of the last to subject the work to a further wiping action, and means for securing the upper at approximately the end of said movement of the wiper to an innersole carried by the last.

19. A machine of the class described, having in combination, means for wiping an upper over the rear edge of a last, means for securing the upper to an innersole mounted upon the last, a gage for positioning the shoe formed to have engagement with opposite sides of the rear end of the shoe intermediate the sole and the cone of the last, and means for sustaining said gage for yielding movement in the direction of the height of the last.

20. A machine of the class described, having in combination, means arranged for engagement with opposite sides of the rear end of a shoe adjacent to the sole for adjusting the portion of the shoe adjacent to the sole laterally into a predetermined position, means arranged for engagement with the rear end of the shoe at a point intermediate the sole and the cone of the last for adjusting said part of the shoe laterally into a predetermined position, and nail driving mechanism arranged to insert a fastening in the rear face of the shoe.

21. A machine of the class described, having in combination, a stationary rest, fastening-inserting mechanism arranged to in-

sert a fastening in the rear face of a shoe held in engagement with the rest, a gage having converging surfaces arranged to receive the rear end of the shoe between them, said gage being arranged normally in advance of said rest and constructed for movement with the shoe as said shoe is moved into working position.

22. A machine of the class described, having in combination, means for supporting a last and parts to be assembled arranged loosely upon the last, means for adjusting the upper forwardly along the sides of the last at the heel and for holding the ends of the counter against the sides of the last, and means for thereafter securing the upper to an innersole mounted upon the last.

23. In a machine of the class described, a last supporter arranged for movement longitudinal of the last, means for yieldingly sustaining the supporter in said movement, means for guiding a last mounted upon the supporter into operative position in the machine comprising members arranged to engage the sides of the last at the heel, means for yieldingly pressing said members against the last, and a device arranged for engagement with the sole of the last at the heel for positioning the last with respect to its height relatively to said members.

24. A machine of the class described, having in combination, a last supporter arranged for movement to and from working position, means for wiping the upper over the edge of the last in the movement of the last into working position, means for thereafter automatically pressing the upper against the face of the last in substantially the plane of the sole, and means for automatically securing the upper to an innersole mounted upon the last at the part acted upon by said wiping means and pressing means.

25. A machine of the class described, having in combination, mechanism for inserting a fastening and means for guiding a shoe into a position wherein a predetermined part of its heel portion lies in operative relation to said mechanism, said means constructed and arranged for wiping the upper forwardly along the sides of the shoe at the heel preparatory to the operation of said mechanism.

26. A machine of the class described, having in combination, a last supporter arranged for movement to and from working position, a wiper arranged in the path of the last for wiping the upper over the edge of the last in the movement of the last supporter into working position, means for automatically moving the wiper to subject the work to a further wiping action, and means for automatically securing the upper to an innersole carried by the last at approxi-

mately the end of said movement of the wiper.

27. A machine of the class described, having in combination, a last supporter arranged for movement to and from working position, a wiper arranged in the path of the last for wiping the upper over the rear edge of the last, devices arranged in the path of the last for wiping the upper forwardly along the sides of the last at the heel and means for securing the upper at the heel to an innersole mounted upon the last.

28. In a machine of the class described, the combination with stationary mechanism for inserting a fastening in the rear end of a last between the bottom and the cone of the last, of means for adjusting the last laterally into position to receive said fastening in its rear end at a point one side of a median line of the last.

29. In a machine of the class described, the combination with means for supporting a last and shoe carried thereby for movement into and out of working position, of mechanism for inserting a fastening in the rear end of a last between the bottom and the cone of a last, and means for adjusting

the last upon its supporting means by engagement with the opposite sides of the shoe into position to receive said fastening 30 in its rear end at a point one side of a median line of the last.

30. A machine of the class described, having in combination, means arranged for engagement with opposite sides of the rear 35 end of a shoe adjacent to the sole for adjusting the portion of the shoe adjacent to the sole laterally into a predetermined position, means arranged for engagement with the rear end of the shoe at a point intermediate 40 the sole and the cone of the last for adjusting said part of the shoe laterally into a predetermined position, and nail driving mechanism arranged to insert a fastening in the rear end of the shoe at a point between 45 the bottom and the cone of the last and at one side of a median line of the last.

In testimony whereof I have signed my name to this specification in the presence of two subscribing witnesses.

ORRELL ASHTON.
